ROTARY WINDOW CONSTRUCTION

Paul J. Howard, Los Angeles, Calif.

Application November 9, 1953, Serial No. 390,955

12 Claims. (Cl. 268—104)

This invention relates to windows and is particularly directed to improvements in rotary windows of the type employed in buildings or other structures.

This invention finds particular usefulness in connection with window constructions for dwellings, office buildings, hotels, apartments, etc. but these are by way of illustration and the invention is not limited to such uses.

Rotary windows of various types have been proposed heretofore but such devices have not met with any general acceptance and have not enjoyed commercial success. In general, the prior attempts to produce satisfactory rotary window constructions have met with failure because the devices were too complicated and expensive and because they failed to turn freely. Furthermore, they did not provide weather-tight joins and were difficult to install and maintain.

It is the principal object of this invention to provide an improved rotary window construction in which the above named deficiencies of prior devices are minimized or altogether eliminated.

It is another object of this invention to provide a rotary window construction having a plurality of circular disks mounted to turn on a common axis, together with novel means accessible from the inside of the room for turning any one or all of the disks and for maintaining them in selected position.

It is another object of this invention to provide such a device which may readily be proportioned to fit within buildings of otherwise conventional construction.

Another object is to provide such a device in which the lower half of each disk is concealed within the wall and only the upper half is visible.

Another object is to provide adjacent disks with generally semi-circular sections which are formed of glass, screen, curtain materials and the like so that by turning each of the disks individually any desired combination of such materials can be achieved. Thus by turning the individual disks the window opening may be entirely unobstructed and fully open, or covered only by the screen, or covered by either transparent glass or translucent glass, curtained or entirely shut-off by an opaque surface.

A more particular object is to provide a rotary window construction employing a plurality of co-axial disks. Each of the disks having more than two sections and a stationary section on the frame work symmetrically positioned between window openings on either side.

Other related details and advantages will appear hereinafter.

Referring to the drawings:

Figure 1 is a front elevation of a window construction embodying my invention as it appears from the outside of the building.

Figure 2 is a top plan view.

Figure 3 is a sectional elevation taken substantially on the lines 3—3 as shown in Figure 1.

Figure 4 is a sectional plan view taken substantially on the lines 4—4 as shown in Figure 3.

Figure 5 is a front elevation showing a portion of the device taken substantially on the lines 5—5 as shown in Figure 3.

Figure 6 is an elevation view partly broken away taken substantially on the lines 6—6 as shown in Figure 3.

Figure 7 is a fragmentary detail taken substantially on the lines 7—7 as viewed in Figure 1.

Figure 8 is an elevation partly in section showing a modified form of my invention.

2

Figure 9 is a sectional elevation taken substantially on the lines 9—9 as shown in Figure 8.

Figure 10 is a sectional plan view taken substantially on the lines 10—10 as shown in Figure 9.

5 Figure 11 is a front elevation of the device taken substantially on the lines 11—11 as shown in Figure 9.

Figure 12 is an elevation partly in section taken substantially on the lines 12—12 as shown in Figure 9.

10 Figure 13 is an elevation view partly in section taken substantially on the lines 13—13 as shown in Figure 9.

In the drawings:

The rotary window construction embodying my invention includes a plurality of rotary disks 10, 11, and 12, mounted co-axially on a stationary frame work generally designated 13. The frame work defines a semi-circular window opening, generally designated 9. Each of the disks is circular in outline and each is provided with two generally semi-circular sections or areas. The outside disk 10 may be provided with window glass 14 on one section and screen 15 on the other. The disk 11 may carry an adjustable Venetian blind ventilator device 16 on one section and may have an opening or void 17 on the other. The inner disk 12 may have tinted glass 18 on one section and an opening or void 19 on the other. 20 A solid sheet 20 of metal or any other suitable material covers the lower half of the device on the inside so that only the upper portion of the disks are visible from the interior of the building.

25 In the general scheme of operation, the individual disks 10, 11, and 12, can be turned to present either of their two sections in the upper half of the window opening. A maximum amount of light is admitted when the disks 11 and 12 have their open parts 17 and 19 in the window opening, the outer disk 10 presenting either the window glass 14 or window screen 15 to cover the opening. 30 Similarly, other combinations can be achieved by suitable turning of the individual disks 10, 11, and 12.

The frame work generally designated 13 includes the inner frame rail 21 and the outer frame rail 22. These 35 may be rectangular in shape and spaced apart so that their maximum width overall is substantially the same as the outside wall of the building. The frame rails may be fixed to the wall by any suitable or convenient fastening devices 23. A structural plate 24 is connected to the inner frame rail 21 by means of fastening elements 25. Similarly, another structural plate 26 is fixed to the outer frame rail 22 by means of fastening elements 27, this plate covers the entire lower half of the window opening on the outside of the structure.

40 A circular structure generally designated 28 includes a pair of circular rails 29 and 30 which are connected by a circular spacer element 31. The circular rails 29 and 30 are connected to the structural plates 26 and 24 respectively by means of suitable fastening elements 32.

45 The fastening elements also act to secure the annular ring 33 to the structural plate 24 and to secure the annular member 34 to the structural plate 26. The outer disk 10 turns within the member 34, the center disk 11 turns within the spacer element 31 and the inner disk 12 turns within the circular rail 30. An annular filler piece 35 may be interposed between the disk 11 and the structural plate 26. Sufficient clearance is present between the outer rims of the disks 10, 11, and 12 to permit them to turn readily within the enclosing portions of the frame work 13.

50 Means are provided for rotatably supporting the disks in co-axial relationship and as shown in the drawings this means includes the shaft 36 which has an enlarged portion 37 fixed with respect to the hub 38 of the disk 10. The shaft 36 and disk 10 turn as a unit. The disk 11 is provided with a hub 39 which turns freely on the shaft 36 and which is provided with an integral axial sleeve 40. A gear 41 is fixed on this sleeve by means of a set screw 42. From this description, it will be understood that the center disk 11 and the gear 41 turn as a unit.

55 The inner disk 12 is provided with a hub 43 having an axial projection 44. A gear 45 is fixed to this projection by means of a set screw 46. The hub 43 and projection 44 turn on the sleeve 40 so that the disk 12 and gear 45 turn as a unit. Suitable bearing means are provided for 60 rotatably supporting the shaft and hubs of the disks. As 65

shown in the drawings, this bearing means includes a supporting member 47 carried on the annular filler piece 35 by means of the horizontal spokes 48. A second supporting bearing is provided by the member 49 which is mounted on the removable strut 50. This removable strut 50 is held in place by means of the wing nuts 51 and threaded elements 52.

The outer disk 10 may be turned relative to the frame work 13 by means of the crank 53 mounted on the inner end of the shaft 36. A portion of the shaft 36 is threaded, as shown at 54, to receive the clamping nut 55. Tightening of this nut 55 on the threads 54 serves to clamp the shield or guard 56 against the stationary elements 29, 49, and 50, and to clamp the outer rim of the window disk 10 against the stationary circular member 34.

As shown in Figure 4, the strut 50 carries a pair of parallel shafts 57 and 58. Suitable bearing means 59 are provided for rotatably supporting the inner ends of these shafts. The outer ends are rotatably supported in bearings 60 carried on the housing 56. The housing is attached to the removable strut 50 by means of suitable fastenings 61. The handwheel 62 is fixed on the outer end of each of the shafts 57 and 58. The gear 63 is fixed to the shaft 57 by means of the set screw 64. Similarly, the gear 65 is fixed to the shaft 58 by means of the set screw 66. Turning of the handwheel 62 on shaft 57 is, therefore, effective to turn gear 63 and meshing gear 45 thereby turning the window disk 12. Similarly, turning of the handwheel 62 on shaft 58 is effective to turn gear 65 and meshing gear 41 and thereby turn the window disk 11. The shaft 58 may be locked in selected position by means of the clamp nut 67 and, similarly, the shaft 57 may be locked in selected position by means of the clamp nut 68.

From the above description, it will be understood that the window disk 10 is turned by means of the crank 53 and locked by means of the clamp nut 55. Similarly, window disk 11 is turned by means of the shaft 58 and held in position by means of the clamp nut 67. The inner window disk 12 is turned by means of the shaft 57 and clamped in selected position by means of the clamp nut 68.

Any one of the window disks may be turned without affecting any of the others.

A feature of my invention resides in the fact that clamping of the shaft 36 to prevent rotation thereof is effective to clamp the rim of the outer window disk 10 against the frame work 13 and thereby effectively to seal the window structure against entry of water. The channel 69 formed in the member 34 prevents rain water from gravitating into the interior of the window structure.

While each of the window disks has been shown and described as having only two sections, which sections are substantially semi-circular, it is recognized that a greater number of sections can be provided on any one of the window disks. In the particular form of the invention illustrated, the window disk 10 has a screen 15 filling one of the two sections and this screen is held in place by means of suitable fastening elements 70. The other half section of disk 10 is formed of window glass 14 which is held in place by putty 71 or by any other convenient means.

The window disk 11 has a void or opening 17 comprising one of its sections within its outer rim. The other section may comprise an opaque sheet or plate 72 carrying the Venetian blind structure 16. This structure 16 may take the form of commercially available louvres 73 mounted within a sub-frame 74 and having mechanism generally designated 75 for simultaneously shifting the position of the louvres 73. A control knob 76 is available for manual action. When the disk 11 is shifted from the position shown in Figure 3 to bring the Venetian blind mechanism 16 into the upper half of the window structure, the control knob 76 is accessible through the opening 19 provided in the window disk 12. The opening 19 comprises one section of the window 12 and the translucent glass 18 provides the other section. The glass 18 may be held in place by putty 77 or by any other convenient means. This glass 18 transmits light but it is not possible to see through it.

With the particular form of window disks shown in Figures 1-7, the maximum amount of light is obtained when the parts are in the position shown in Figure 3. The screen 15 may be brought into position instead of

the transparent glass 14 simply by turning the crank 53. For privacy, the translucent glass may be swung into position by turning the shaft 57. If it is desired to close the window entirely against entrance of both light and air the window disk 11 may be turned by means of the shaft 58 to bring the opaque member 72 into position. If the louvres 73 are closed no light or air is admitted. Opening of the louvres permits the desired amount of air to be admitted into the room.

In the modified form of my invention shown in Figures 8-13, there is shown a rotary window construction especially adapted for installation in the bathroom of a dwelling. Three co-axial window disks 10a, 11a, and 12a, are provided and these are mounted for co-axial turning movement in a manner similar to that described above. The frame structure 13a is also similar in many respects to that previously described.

This form of my invention differs primarily in that the window disks 11a and 12a are provided with six

sections instead of two and the frame work provides a stationary cabinet or shelf in the central portion of the upper of the window structure and between the disks 10a and 11a. Window openings generally designated 78 and 79 are defined by the frame on opposite sides of the cabinet 80. These window openings are of the same size and shape as the cabinet 80 and constitute a segment of a circle. This stationary cabinet or shelf space is shown at 80 and includes the horizontal shelves 81, 82, and 83, which extend between diverging stationary ribs 84. A rear plate 85 in the shape of a segment of a circle forms the rear boundary of the cabinet. The plate 85 does not extend beyond the outer edges of the diverging stationary ribs 84. The stationary horizontal ribs 86 are joined with the ribs 84 and with the semi-circular rim 87. These horizontal ribs provide shelf space 88.

The cabinet 80 is proportioned to occupy an area equal to one-sixth the area of the window disks and is shaped to conform to the shape of each of the sections of disks 11a and 12a.

The window disk 10a is preferably provided with two large semi-circular sections, as previously described. This disk 10a is best shown in Figure 11. The disk 11a is best shown in Figure 12 and may include two curtain sections 89 separated by a void or open section 90. The other three sections 91, 92, and 93, of the disk 11a are likewise void or open. In the position shown in Figure 12, the open section 92 permits access to material placed on the shelves 81, 82, and 83. The open sections 91 and 93 permit access to materials on the horizontal shelf 88. The sections are defined between spokes 94 which radiate from the hub structure 95 to the circular rim 96.

The inner window disk 12a is best shown in Figure 8. This disk preferably has a mirror in sections 97 and 98, voids or open spaces in sections 99 and 100, and sheet metal blanks 101 and 102.

The window disks 10a, 11a, and 12a, are mounted in the manner previously described and arranged so that they may be independently turned and independently held in position. The outer window disk 10a is fixed on the rotary shaft 103, the intermediate window disk 11a is carried on the sleeve 104 and the inner window disk 12a is mounted on the extension 105 of the hub 106. The window disk 10a is turned by means of crank 107 and held in selected position by means of the wing nut 108. The clamp action of the wing nut 108 brings the rim 109 into sealing engagement with the stationary member 110 on the frame work 13a. The window disk 11a is turned from handwheel 111 by way of shaft 112, gear 113 and meshing gear 114. The inner window disk 12a is turned by means of handwheel 115 acting through shaft 116, gear 117, and meshing gear 118. The wing nuts 119 and 120 serve to clamp the shaft 112 and 116 respectively in the desired position. The window disk 11a may be turned to position the curtains 89 over the window openings on opposite sides of the cabinet, if desired, or may be turned to the position shown in Figure 12 in which the curtains 89 are positioned out of sight behind the structural sheet 121 which covers the entire lower half of the rotary window construction. The outer window disk 10a can be turned to either of these positions to provide either glass or screen for the window openings on each side of the central cabinet 80. The window disk 12a may be turned to bring either of the mirror sections into place in front of the central cabinet 80 and to place the openings 99 and 100 or the blank metal

sections 101 and 102 in front of the window openings. Access to articles placed on the shelves 88 is obtained when the void or open sections 99 and 100 are in the position shown in Figure 8. The inner window disk 12a must be turned from the position shown in Figure 8 in order to gain access to the shelves within the cabinet 80.

A light 122 may be centrally mounted on the frame work above the position of the cabinet 80. This light may be controlled from the switch 123. Suitable electrical outlets 124 for operating electric shavers, etc., may be mounted adjacent the switch 123. If desired, a recess 125 for a drinking glass 126 may be provided on the frame work 13.

Having fully described my invention, it is to be understood that I do not wish to be limited to the details herein set forth, but my invention is of the full scope of the appended claims.

I claim:

1. In a rotary window construction, the combination of: a stationary frame defining a window opening, a plurality of coaxial window disks each divided into a plurality of sections, one of the disks having a circular rim adapted to clamp against an outward facing element of the frame to form a peripheral seal, a shaft rotatably mounted upon the frame and fixed relative to the said disk, means rotatably supporting another disk upon said shaft at a location inward from said seal, means for turning the shaft and for turning the other disk independently to align any desired disk sections with said window opening, and common means for securing the shaft against turning and for clamping the first said disk in sealing relationship.

2. In a rotary window construction, the combination of: a plurality of coaxial window disks each divided into a plurality of sections of the same size, a stationary frame defining a window opening of the same size as said disk sections, one of the disks having a circular rim adapted to clamp against an outward facing element of the frame to form a peripheral seal, a shaft rotatably mounted upon the frame and fixed relative to the said disk, means rotatably supporting another disk upon said shaft at a location inward from said seal, means for turning the shaft and for turning the other disk independently to align any desired disk sections with said window opening, and common means for securing the shaft against turning and for clamping the first said disk in sealing relationship.

3. In a rotary window construction, the combination of: a stationary frame defining a semicircular window opening, a plurality of coaxial window disks each divided into two equal semicircular sections, one of the disks having a circular rim adapted to clamp against an outward facing element of the frame to form a peripheral seal, a shaft rotatably mounted upon the frame and fixed relative to the latter said disk, means rotatably supporting the other disks upon said shaft at locations inward from said seal, means for turning the shaft and for turning the other disks independently to align any desired disk sections with said window opening, and common means for clamping the shaft against turning and for clamping the said disk in sealing relationship.

4. In a device of the class described, the combination of: a stationary frame defining a window opening, a plurality of coaxial window disks, each disk being divided into a plurality of sections of equal size, a shaft fixed to one of the disks and rotatably mounted on the frame, the latter said disk having a circular rim adapted to clamp against an outward facing element of the frame to form a peripheral seal, means for turning the shaft, common means for clamping the shaft against turning and for clamping the said disk against said frame element, a sleeve rotatably mounted on the shaft and fixed to a second disk, a hub rotatably mounted on the sleeve and fixed to a third disk, and gear means for turning the sleeve and hub independently, whereby any desired disk sections may be aligned with said window opening.

5. In a device of the class described, the combination of: a stationary frame defining a semi-circular window opening, a plurality of coaxial window disks each having two semicircular sections, a shaft fixed to one of the disks and rotatably mounted on the frame, the latter said disk having a circular rim adapted to clamp against an outward facing element of the frame to form a peripheral seal, means for turning the shaft, common means for clamping the shaft against turning and for clamping the 85

said disk against said frame element, a sleeve rotatably mounted on the shaft and fixed to a second disk, a hub rotatably mounted on the sleeve and fixed to a third disk, a gear fixed on the sleeve, a gear fixed on the hub, and means for turning said gears independently, whereby any desired disk sections may be aligned with said window opening.

6. In a device of the class described, the combination of: a stationary frame defining a window opening in the shape of a segment of a circle, a plurality of coaxial window disks each having a plurality of segmental sections of the same size as the window opening, a shaft fixed to one of the disks and rotatably mounted on the frame, the latter said disk having a circular rim adapted to clamp against an outward facing element of the frame to form a peripheral seal, means for turning the shaft, common means for clamping the shaft against turning and for clamping the said disk against said frame element, a sleeve rotatably mounted on the shaft and fixed to a second disk, a hub rotatably mounted on the sleeve and fixed to a third disk, a first gear fixed on the sleeve, a second gear fixed on the hub, a third gear meshing with the first gear, a fourth gear meshing with the second gear, a common housing enclosing said gears, and means projecting from said housing for turning the third and fourth gears independently, whereby any desired disk sections may be aligned with said window opening.

7. In a rotary window construction, the combination of: a stationary frame defining two separate window openings, the openings being of the same size and constituting segments of a circle, the openings being spaced apart by a frame structure having the same shape as the said openings, a plurality of coaxial window disks, one of the disks being positioned on one side of said frame structure, the other of the disks having a plurality of sections of the same size and shape as said openings and being adapted for alignment therewith, the latter said disk being positioned on the other side of said frame structure, and means for independently turning each of the disks.

8. In a rotary window construction, the combination of: a stationary frame defining two separate window openings, the openings being of the same size and each constituting one of six equal segments of a circle, the openings being spaced apart by a frame structure having the same segmental shape as the said window openings, a plurality of coaxial window disks, one of the disks being positioned on one side of said frame structure, the other of the disks having six sections of the same size and shape as said openings and being adapted for alignment therewith, the latter said disk being positioned on the other side of said frame structure, and means for independently turning each of the disks.

9. In a rotary window construction, the combination of: a stationary frame defining two separate window openings, the openings being of the same size and constituting segments of a circle, the openings being spaced apart by a frame structure having the same shape as the said openings, a plurality of coaxial window disks, at least one of the disks having a plurality of sections of the same size and shape as said openings and being adapted for alignment therewith, said disk being positioned on one side of said frame structure, another of said disks being positioned on the other side of said frame structure, a shaft rotatably mounted on the frame and fixed relative to the latter said disk, means rotatably supporting the other of said disks upon said shaft, means for turning the shaft, and means for independently turning the said other disk.

10. In a rotary window construction, the combination of: a stationary frame defining two separate window openings, the openings being of the same size and constituting segments of a circle, the frame including a cabinet having the same shape as the said window openings and positioned therebetween, a plurality of coaxial window disks, at least one of the disks having a plurality of sections of the same size and shape as said window openings and being adapted for alignment therewith, the latter said disk being positioned on one side of the cabinet and the other disks being positioned on the other side of the cabinet, and means on the frame supporting the disks for independent turning movement.

11. In a rotary window construction, the combination of: a stationary frame defining two separate window openings, the openings being of the same size and con-

stituting segments of a circle, the openings being spaced apart by a frame structure having the same shape as the said openings, a plurality of coaxial window disks, at least one of the disks having a plurality of sections of the same size and shape as said openings and being adapted for alignment therewith, one of the disks having a circular rim adapted to clamp against an element of the frame to form a seal, a shaft rotatably mounted upon the frame and fixed relative to the said disk, means rotatably supporting another disk upon said shaft, means for turning the shaft and for turning the other disk independently to align any desired disk sections with said window openings, and common means for securing the shaft against turning and for clamping the first said disk in sealing relationship.

12. In a rotary window construction, the combination of: a stationary frame defining two separate window openings, the openings being of the same size and constituting segments of a circle, the frame including a cabinet having the same shape as the said window openings and positioned therebetween, a plurality of coaxial win-

dow disks, at least one of the disks having a plurality of sections of the same size and shape as said window openings and being adapted for alignment therewith, the latter said disk being positioned on one side of the cabinet and the other disks being positioned on the other side of the cabinet, a shaft fixed to one of the disks and rotatably mounted on the frame, means for turning the shaft, a sleeve rotatably mounted on the shaft and fixed to a second disk, a hub rotatably mounted on the sleeve and fixed to a third disk, and gear means for turning the sleeve and hub independently whereby any desired disk sections may be aligned with said window openings.
